DECORATED HARD SURFACE COVERING
AND METHOD OF MANUFACTURING
THE SAMEJ. Clarence McCarthy, Lancaster, Pa., assignor to
Armstrong Cork Company, Lancaster, Pa., a
corporation of Pennsylvania

Application May 26, 1930, Serial No. 455,693

4 Claims. (Cl. 91—67.9)

This invention relates to decorated hard surface coverings and method of manufacturing the same, and is herein particularly described as applied to the manufacture of floor coverings by the 5 decoration of felt base material.

In the manufacture of felt base floor coverings, it is common practice to print an over-all 10 decoration in oil paints and to protect the same by a top coating of lacquer or the like. It has also been proposed to obtain certain decorative 15 effects by forming a decorative base and applying decorative elements to portions only of the material so that the base decoration shows therebetween. This invention is more specifically described and claimed in my copending application 15 Serial No. 320,948, filed November 21, 1928. The material last referred to may or may not be protected with an overlying coat of lacquer, as desired.

20 Lacquer coatings, generally, while they are of value in materially lengthening the life and brightness of the floor coverings, are, from their very nature, relatively so thin that it is necessary to renew them from time to time if full protection for the pattern is to be obtained. Fluid 25 lacquer contains a large amount of solvent and only a relatively small quantity of material which remains on the surface to which the lacquer has been applied, after evaporation of the solvent, and therefore such coats, from their very nature, are 30 penetrative in character. Most printed floor coverings are made by printing the design on an all-over base coat. The base coat is usually a relatively low-priced oil paint and is somewhat porous in its nature. Therefore, there is a tendency 35 for the lacquer to travel into the base coat and to be largely absorbed thereby.

In printed floor coverings of the ordinary type, the base coat is entirely covered by decorative 40 paints, but as hereinafter described, this is not true in the present invention.

While a floor covering naturally wears to some extent, the greatest factor contributing to deterioration thereof is the solvent action of soap 45 and water on the oils of the paint. The soap saponifies the oils in the paint and this, coupled with the mechanical attrition resulting from scrubbing, results in a relatively rapid removal of the paint. This condition is emphasized where 50 there are upstanding paint decorations, as provided in my copending application above referred to. Such floor coverings, while they have numerous advantages from the standpoint of appearance and otherwise, are somewhat subject to rapid 55 deterioration by reason of the fact that soap or

soapy water may collect in the depressions of the material and, further, because the edges of the upstanding paint decoration provide "shoulders" which may be readily attacked during scrubbing.

I have found that these difficulties may be overcome and a highly superior product obtained by forming a base coat, applying a suitable protective coat thereover, and then applying further decoration over the protective coat if desired. 10 A final protective coat lying over the last applied decorations may be employed. The base coat will ordinarily be executed in an oil paint and may in itself possess decorative qualities, or a decoration may be applied thereto in the form 15 of a thin paint, an ink, a metallic paint or the like. By reason of the porous nature of the oil paint, I prefer to employ a protective coating of varnish. The varnish, even though relatively thin, contains considerably more solid matter 20 than the commercial lacquers, and is more effective for closing pores and forming a continuous protective coating over the base. After this varnish has dried, the overlying decorations are applied. These may be put on by printing, stencil- 25 ing, or any other suitable operation. Ordinarily, these decorations will be laid on relatively thick, and will therefore be upstanding from the general level of the protective coating. They will be so placed that part of the base coat will show between them, and since the varnish is transparent or translucent, its decorative qualities will be apparent between the overlying paint decoration. The words "transparent" and "translucent" are 30 hereinafter used equivalently.

After the overlying decorative elements have 35 been dried, a final protective coating, as of lacquer, may be applied.

If desired, the varnish or the final lacquer coat 40 may be tinted or colored. In this way, many desirable effects can be obtained, particularly since the varnish coat will be obscured except between the last applied decorative elements.

The oil paints are relatively non-porous, and, although the lacquer coat may be absorbed to 45 some degree by the overlying paint decorations, there will be a good lacquer film over the paint and a relatively thicker film in the depressions between the overlying decorative elements. This film, by reason of the surface-tension and 50 capillary of the lacquer when applied, will form well rounded fillets adjacent the shoulders of the overlying decorations and afford the utmost protection therefor. The lacquer and the varnish are mutually adherent and cooperate to form a 55

matrix in which the paint body forming the overlying decorative fillets will be encased. The material is therefore well protected at all points and has superior mechanical qualities on this account.

5 In the accompanying drawings illustrating a present preferred embodiment of the invention,

Figures 1 to 5 inclusive, are diagrammatic views illustrating successive steps in the manufacture of my improved product;

10 Figures 1p to 4p, inclusive, are views corresponding to Figures 1 to 4 and showing the product after each step in the manufacturing operation;

Figure 6 is a top plan view of a portion of the finished material; and

15 Figure 7 is a sectional view thereof.

Referring first to Figures 1 and 1p, there is shown a web 2 of felt base material which is moved under a doctor blade 3 behind which there is maintained a pool 4 of oil paint. As the material passes under the doctor blade, it is supported on a rubber web or blanket 5. The doctor blade 3 is notched and serves to meter the amount of paint supplied to each unit of area of the web 2. The paint is flattened by a spring-like doctor blade 6, thus producing a smooth, uniform, continuous base coat 7.

The coating mechanism illustrated diagrammatically in Figure 1 is in the invention of Daniel S. Holt and is more fully described and claimed in 30 his application Serial No. 589,860, filed Jan. 30, 1932.

After the coating material has been stoved, there may be applied an open-work design in the nature of a textured effect. Such decoration may 35 extend over the entire area of the paint coat 1 or on certain selected portions only thereof, e. g., it may be applied only to part or all of the portions of the base coat which are ultimately to be left exposed. Ordinarily, however, it is preferred to print it in an open design over 40 the entire area of the base coat, since this removes any problem, on subsequent printing, of registration. The means for applying this decorative coat is indicated in Figure 2. The material travels over a drum 8 and the decorative ink is 45 applied by means of an offsetting roller 9 which receives ink or paint from a pattern roll 10. The pattern roll is supplied with ink through ink rollers 11 and a doctor roll 12 and moves between 50 one of the inking rollers 11 and a fountain roll 13 in an ink fountain 14. The resulting material is shown in Figure 2p, where the ink decoration is indicated at 15.

I have found that the overlying protective 55 varnish coat may be applied while the ink decorations 15 are still wet. In Figure 3 there are indicated spray guns 16 which deposit a thin film of varnish 17 over the entire surface of the goods, as shown in Figure 3p. After the material leaves 60 the spray guns it is fed to a stove, not shown, where the varnish is dried. The varnish fills the pores of the paint coat and provides an overlying transparent or translucent seal coat. Of course, the ink or oil paint may be dried prior to 65 application of the varnish coat, if desired. In such case, the varnish will ordinarily be applied by a doctor blade or a rubber roll.

The ink decoration is very thin—about .0002 70 inch. Because of this thinness, it is necessary to give the ink adequate protection. The varnish is several times as thick, and very tough in character, affording the desired protection for the ink as well as acting as a sealing agent.

Figure 4 indicates diagrammatically a block 75 printing machine having printing heads 18 for

applying overlying paint decorations 19. It will be noted that these are relatively thick and stand up from the surface of the varnish coat 17. After the material has again been stoved to dry the oil paint, the material is passed between rolls 20 5 behind the upper of which a pool 21 of lacquer is maintained. A film of lacquer is thus laid over the entire top surface of the goods and the film is dried in a hood 22, having a pipe 23 for taking off the evaporated solvent. The product is now 10 finished and may be rolled up as indicated at 24.

Figures 6 and 7 show the finished material to relatively large scale. The overlying lacquer coat is indicated at 25, and it will be noted that this coat is particularly heavy adjacent the shoulders 15 of the decorations 19 as indicated at 26. The lacquer film lies directly over the varnish coat 17 between the decorative elements 19 and cooperates therewith to form a matrix completely 20 enclosing the paint bodies which form the last 25 applied decorative elements.

It will be noted that the lacquer film lies at a relatively low level between the decorative elements 19. While the film, as laid, will have a substantially plane top surface, the depressions 25 will appear, by reason of the fact that a very large percentage of liquid lacquer is solvent, which is evaporated in the hood 22. The lacquer will be relatively thicker in the depressions than on top of the decorative elements 19, thus affording 30 still further protection for the shoulders of such elements.

The pattern shown in Figure 6 is illustrative only of the process, and it will be understood that the invention may be carried out in any number 35 of different patterns. In Figure 6, the base coat 7 and the textured decoration 15 are exposed between the decorative elements 19. It will be seen that a wide variety of effects may be obtained, particularly by the use of different colors in the 40 several decorative elements, the base coat, the varnish coat, or the lacquer coat.

I have illustrated and described a present preferred embodiment of the invention. It will be understood, however, that it is not limited to the 45 form shown, but may be otherwise embodied or practiced within the scope of the following claims.

I claim:

1. As an article of manufacture, a decorated 50 flexible hard surface covering comprising a flexible base, a relatively porous base coat on said base, a decoration on said base coat lying substantially flat thereon with portions of the base coat exposed, an overlying transparent protective coat of varnish-like consistency sealing the pores in said base coat, and decorative elements executed in a material of such body as to stand in relief overlying portions only of the protective coat with portions of the base coat and the first decoration visible therebetween.

2. As an article of manufacture, a decorated 55 flexible hard surface covering comprising a flexible base, a relatively porous base coat on said base, a decoration on said base coat executed in a light-bodied material with such design as to leave portions of the base coat exposed, an overlying transparent protective coat of varnish-like consistency sealing the pores in said base coat and forming a relatively impervious surface, decorative elements executed in a material of such body as to stand in relief overlying portions only of the protective coat with portions of the base coat and the first decoration visible therebetween, and a protective coat of lacquer overlying said decora- 60 65 70 75 80 85 90 95 98

tive elements and the exposed portions of the first-mentioned protective coat.

3. As an article of manufacture, a decorated flexible hard surface covering comprising a flexible base, a relatively porous base coat on said base, a textured decoration lying substantially flat on said base coat with portions of the base coat exposed, an overlying transparent protective coat of varnish sealing the pores in said base coat, decorative elements executed in an oil paint overlying portions only of the protective coat with portions of the base coat and the first decoration visible therebetween.
- 10 4. As an article of manufacture, a decorated

flexible hard surface covering comprising a flexible base, a relatively porous base coat on said base, a textured decoration executed in ink lying substantially flat on said base coat with portions of the base coat exposed, an overlying transparent protective coat of varnish sealing the pores in said base coat, decorative elements executed in an oil paint overlying portions only of the protective coat with portions of the base coat and the first decoration, being visible therebetween, and a 10 transparent protective coat of lacquer overlying said decorative elements and the exposed portions of the first-mentioned protective coat.
